INVENTOR:

H. D. Caruso

UNITED STATES PATENT OFFICE.

HENRY D. CARUSO, OF EAST ORANGE, NEW JERSEY, ASSIGNOR TO THE AMERICAN LEAD PENCIL COMPANY, OF NEW YORK.

PENCIL OR CRAYON HOLDER.

SPECIFICATION forming part of Letters Patent No. 362,933, dated May 17, 1887.

Application filed June 21, 1884. Renewed March 26, 1887. Serial No. 232,571. (No model.)

To all whom it may concern:

Be it known that I, HENRY D. CARUSO, a citizen of the United States, and a resident of East Orange, in the county of Essex and State 5 of New Jersey, have invented certain new and useful Improvements in Pencils, of which the following is a specification.

My invention relates more particularly to pencils of the class in which the lead or crayon 10 slides in its sheath or holder and is adapted to be projected by simple pressure upon the butt of the pencil, or to be pushed back within its sheath by pressure upon the point of the crayon or lead.

15 In pencils of this class as hitherto constructed it is found that, owing to the lubricating nature of the graphite, the lead finally works loosely in its sheath, and is not, therefore, properly retained in either its projected 20 or retracted position.

The principal aim of my invention is to overcome this difficulty; and to this end my invention consists in the combination, with the sheath having a bore in which the crayon 25 slides, of a slot in said sheath cut through to the bore and an elastic detaining device mounted in the slot and bearing against the side of the pencil with an elastic pressure.

A further aim of my invention is to make 30 a simple and cheap pencil in which the crayon or lead may be projected by simply pressing the butt of the pencil upon a table or other object, while it may be pushed back within its sheath by similarly pressing the point of 35 the crayon upon any object; and to this end my invention consists in the novel and simplified combinations shown in the accompanying drawings, and which will be more specifically stated in the claims at the end of the 40 specification.

In the drawings, Figure 1 is a side view of one form of pencil constructed according to my invention. Fig. 2 is a side view of the sheath or case with the cap-piece and sleeve 45 upon the butt removed. Fig. 3 is a longitudinal section of the complete pencil. Fig. 4 is a side view of a modified form of the pencil. Fig. 5 is a longitudinal section of Fig. 4.

A, Fig. 1, indicates the sheath or case, hollow at its center and made preferably of wood. This sheath, like that of the ordinary lead-

pencil, is to be cut away to expose the lead to a greater or less extent, either originally to prepare the pencil for use, or from time to time, as the lead wears down. 55

B indicates the crayon or lead adapted to slide backward and forward in the sheath or case, so that its end may be projected from the point of the pencil for use, or may be pushed back within and covered by the sheath by 60 pressing the point against any object.

C indicates a cap or guard of any suitable kind, adapted to slide on or in the butt of the sheath or case. It consists preferably of a thin sheet-metal tube sliding on the outside of 65 the butt and closed at its outer end, preferably by a piece of soft rubber, serving as an eraser. The crayon or lead B impinges against the sliding cap or guard, but is not attached thereto, and said cap, while protecting the inner end 70 of the crayon or lead from injury, serves to project the point of the crayon from the sheath when pressure is applied to the cap by the finger or otherwise. The end of the cap which works on the end of the sheath has its 75 edge turned over at b, while the sheet-metal ferrule G on the end of the sheath is provided with a corresponding offset at a, against which the edge of the cap-piece abuts when forced outward by the crayon. The crimping c at 80 the other end of the tube or cap serves to limit the movement of the cap in projecting the lead.

It will be observed that the crayon may 85 slide back and forth independently of the cap or guard on the butt, and that there is no rigid connection between them.

Heretofore where the crayon has been attached to the cap directly or indirectly difficulty has been experienced in making the 90 crayon, when attached to the cap, exactly coincide with the bore in the sheath, and the result has been frequent breakage of the crayon, either in inserting it into the sheath or from an attempt to turn the cap on the sheath when 95 the crayon is in place. This difficulty is avoided in my construction, as the crayon is detached or disconnected from the cap and simply abuts against the same.

In order to prevent the crayon from moving 100 freely in its sheath, which it may otherwise do after considerable use, I provide a fric-

tion retaining device bearing against the side of the crayon with an elastic pressure and mounted in or on the sheath or holder, or some part fixed therewith. For this purpose I generally prefer to use simply a piece of soft rubber or other elastic material, but do not limit myself in this respect, as any device whereby an elastic pressure and friction may be applied to the side of the crayon may be employed. 5
10 One of the ways in which such friction retaining device may be applied and held in place is shown in Figs. 2 and 3, where E indicates a piece of soft rubber mounted in a slot or recess cut in the side of the sheath, and held in place 15 by the ferrule G, as indicated. The ferrule is fitted tightly to the sheath A. The slot cut in the side of the sheath extends through to the bore in which the crayon reciprocates, and the rubber bears against the side of said 20 crayon with a friction-pressure.

When the crayon is in place, the manner of using the pencil is as follows: To prepare it for use the butt is pressed firmly against some object so as to cause the cap to slide toward 25 the point and to push the lead in the same direction. If the lead does not then project, the sheath is cut away to the desired distance, so as to expose the lead for use. The length of lead exposed should be no more than is required for ordinary use, and should be equal 30 to or less than the amount of play that the cap is permitted to have upon the butt, so that on pressing the point against some object the crayon may slide to a sufficient distance 35 to have its point sheathed. As the point wears down the sheath may be cut away.

In the modification of my invention shown in Figs. 4 and 5 the ferrule is dispensed with, and the cap-piece or guard C slides directly on the 40 end of the sheath A. The sliding movement of the cap is limited by means of the crimp or bead formed upon it at F, which abuts against the material of the sheath at the extremities

of the depression or annular groove formed on the material of the sheath. 45

The body of the cap-piece or guard C in this instance serves as the sleeve or ferrule whereby the elastic friction-block E is held in its socket.

What I claim as my invention is— 50

1. In a pencil having a crayon or lead adapted to be projected by the application of pressure to the butt, the combination, with the sheath having a slot in its side cut through to the crayon, of a piece of elastic material held in the slot by any suitable means so as to bear against the side of the crayon, as and for the purpose described. 55

2. The combination, with the slotted and perforated sheath and its contained lead, of the piece of elastic material in the slot and an exterior metal sleeve over the slot, as and for the purpose described. 60

3. The combination, with a wooden sheath, 65 as A, having the longitudinal bore for a crayon, and a slot in its side cut through to said bore, of a sheet-metal tube, C, closed at its outer end by a piece of soft rubber and sliding upon the end of the sheath, and an elastic friction-piece bearing against the side of the crayon, as and 70 for the purpose described. 75

4. A pencil or crayon holder consisting of the sheath A, having a slot in its side cut through to the crayon and holding a piece of elastic material, and a sliding cap of sheet metal having a crimp or bead, as at F, working over an annular groove or depression formed in the material of the sheath. 80

Signed at New York, in the county of New York and State of New York, this 19th day of June, A. D. 1884.

HENRY D. CARUSO.
